UNITED STATES PATENT OFFICE.

JAMES R. MOFFATT AND RALPH S. KELSO, OF CHICAGO, ILLINOIS, ASSIGNEES TO UNION SPECIAL MACHINE COMPANY, OF CHICAGO, ILLINOIS, A CORPORATION OF ILLINOIS.

FEEDING MECHANISM FOR SEWING-MACHINES.

1,289,866.

Specification of Letters Patent. Patented Dec. 31, 1918.

Application filed November 14, 1916. Serial No. 181,223.

To all whom it may concern:

Be it known that we, JAMES R. MOFFATT and RALPH S. KELSO, citizens of the United States, residing at Chicago, in the county of Cook, State of Illinois, have invented certain new and useful Improvements in Feeding Mechanism for Sewing Machines, of which the following is a description, reference being had to the accompanying drawing and to the figures of reference marked thereon:

The invention relates to new and useful improvements in feeding mechanisms for sewing machines, and more particularly to a feeding mechanism having a lower feed dog engaging the under face of the fabric and an upper feed dog which co-operates therewith and engages the upper face of the fabric.

An object of the invention is to provide a feeding mechanism of the above character wherein the upper feeding dog is positively moved up and down and forward and backward in a fixed path of travel, and wherein said dog is moved back and forth through a connection with the lower feeding mechanism so that the adjustments of the lower feeding mechanism will also similarly adjust the feeding movements of the upper feed dog.

Another object of the invention is to provide a feeding mechanism of the above character wherein the length of the feeding movement of the upper feed dog may be varied relative to the length of the feeding movement of the lower feed dog.

A further object of the invention is to provide a feeding mechanism of the above character wherein the presser foot co-operating with the lower feed dog is positively moved up and down in a vertical plane only, which movements of the presser foot alternate with the up and down movements of the upper feeding dog, the parts being so timed that the foot and dog are never lifted off the material at the same time.

A still further object of the invention is to provide means for adjusting the lift of the presser foot so that proper clearance may be obtained.

These and other objects will in part be obvious and will in part be hereinafter more fully disclosed.

In the drawings, which show by way of illustration one embodiment of the invention:

55

Figure 1 is a front view of a sewing machine embodying our improvements;

Fig. 2 is a rear view of the same;

Fig. 3 is an end view with parts broken away to show the connection of the lower feeding mechanism to the main shaft;

Fig. 4 is a view partly in end elevation and partly in vertical section in a plane at one side of the main feed bar, showing the feed dogs moved away from the fabric for their return movement, the presser foot being down;

Fig. 5 is a view in part similar to Fig. 4, but showing the feed dogs as engaging the fabric for their feeding stroke, the presser foot being raised;

Fig. 6 is a detail in perspective, showing a portion of the work support, the presser foot, the upper feed dog, and the needle, and also a portion of the fabric guide; and

75

Fig. 7 is a detail in section, showing the means for connecting the feeding mechanism to the lower feeding dog, and the means for raising and lowering the upper feed dog and the presser foot.

80

In carrying out our invention, we have provided a lower feeding mechanism which includes a main feed dog carried by a feed supporting bar which is given the usual movements so as to impart a forward and back and up and down movement to the feed dog. Co-operating with this main feed dog is the upper feed dog or feeding foot and also a presser foot. The upper feed dog or feeding foot is connected to a feeding mechanism which positively raises and lowers said upper feed dog and also positively moves said upper feed dog back and forth. The means for moving the upper feed dog back and forth is connected to the lower feed bar actuating mechanism which moves the main feed dog back and forth. This connection includes an adjustment so that the upper feed dog may be moved in unison with the lower feed dog, or given a longer feeding stroke whereby said upper dog will move at a different speed from the lower feed dog.

95

When, however, this adjustment has been made and the relative feed movements of

100

the feed dogs is determined, they may be adjusted as a whole as to the length of travel by adjusting the actuating mechanism for the main feed bar. The upper feed dog is raised and lowered by a mechanism which includes positive connections with an eccentric on the main shaft, and this mechanism is connected with the presser foot so that the presser foot is positively raised and lowered. The feed dog becomes an abutment for the raising of the presser foot, and the presser foot becomes an abutment for the raising of the feed dog.

Referring more in detail to the drawings, we have shown our improvement as applied to a sewing machine having a supporting bed 1 carrying an overhanging arm 2 in which a needle bar 3 reciprocates. Said needle bar is provided, as herein shown, with a needle 4. The needle bar is reciprocated by a needle lever 5 which is connected to the needle bar by a link 6. This needle lever is oscillated by an eccentric on the main shaft 7 which coöperates with an eccentric strap 8 connected to the needle lever. Coöperating with the needle below the work support is a looper 9 which is oscillated by a link 10 which is connected to the needle lever extension 11. These parts are of the usual construction, and form no part of the present invention.

The work support 12 is carried by the supporting bed 1 and this work support has a feed slot 13 through which the main or lower feed dog 14 operates. Said work support is also provided with a slot 15 which receives the needle 4. The material is held on the work support between feeding movements by a presser foot 16. This presser foot is carried by a presser bar 17 mounted to move vertically only in the work supporting arm 2. Coöperating with the main feed dog 14 is an upper feed dog or feeding foot 18. The main feed dog 14 is carried by a feed bar 19 which is pivoted at 20 to a feed rocker 21. The feed rocker 21 is clamped to a shaft 22 mounted in suitable bearings 23 and 24. The feed rocker 21 is provided with an arm 25 which is connected to a link 26 at its free end. This link 26 is in turn connected to a crank pin 27 which is adjustably connected to a disk 28 on the end of the main shaft 7. By adjusting the position of the pin, the throw of the feed rocker 21 may be varied. As this feed rocker oscillates the feed bar 19 is moved back and forth and, therefore, the adjustments of this pin determine the length of the feeding stroke of the main or lower feed dog.

The main feed bar 19 is raised and lowered by an eccentric 29 which is mounted on the main shaft 7. The upper feed dog 18 is clamped to the lower end of a feed bar 30. This feed bar 30 extends generally in a vertical direction. Said bar has a slot 31 at its

upper end which has sliding engagement with a fulcrum pin 32 threaded into the overhanging arm. This permits the upper end of the bar to move vertically on the fulcrum pin and also to swing about this pin as a pivot point. The feed bar 30 is also provided with an opening 33. A bearing plate 34, larger than the opening, spans the same and rests against the side face of the feed bar 30. This plate 34 is secured to the overhanging arm by a screw 35. The opening 33 is of sufficient size so as to permit the feed bar 30 to move up and down and also to move laterally at this point.

The feed bar 30 is oscillated about the pivot pin 32 by a link 36 which is pivoted at 37 to the feed bar 30. The link 36 at its other end is pivoted at 38 to a depending arm 39 formed integral with or secured to a sleeve 40. This sleeve is mounted so as to oscillate on a shaft 41 which in turn is mounted in suitable bearings 42 and 43 carried by the overhanging arm. Said sleeve 40 is oscillated by an arm 44 which depends from the sleeve 40. The shaft 22 has an arm 45 clamped thereto, and this arm extends upwardly from the shaft. Said arm 45 is formed with a slot 46, while the arm 44 is provided with a slot 47. A link 48 is connected at one end to a pin 49 which is adjustably mounted in the slot 46. The other end of the link 48 is connected to a pin 50 which is adjustably mounted in the slot 47.

As the main feed bar is moved back and forth, the arm 45 will be oscillated, and this through the link 48 will oscillate the sleeve 40 and through the link 36 said sleeve will oscillate the feed bar 30, thus also moving the upper feed dog or feeding foot back and forth. It will be noted that the connections for operating both the main feed dog and the upper feed dog are positive, so that both feed dogs will be positively moved back and forth. If the pins 49 and 50 are properly set in their respective slots 46 and 47, the movements of the upper feed dog will be the same as the movements of the lower feed dog. If these pins 49 and 50 are raised above such a set position, then the movements of the upper feed dog will be greater than the feeding movements of the lower feed dog, while if said pins 49 and 50 are moved below such a set position, then the movements of the upper feed dog will be less than the movement of the lower feed dog. Whatever may be the relative feeding movements of the feed dogs brought about through these adjustments, both of such feeding movements may be simultaneously adjusted by varying the throw of the feed rocker 21 through the shifting of the pin 27 at the end of the main shaft which causes the oscillations of said rocker. In other words, after having once determined the relative movements of the upper and lower feed dogs, these movements

may be lengthened or shortened simultaneously and without disturbing the relative movement between the feed dogs.

The presser bar 17 is connected by an arm 17^a to a guide bar 51 which is movable vertically in suitable bearings in the overhanging arm, the arm 17^a serving to prevent oscillations of the presser bar 17, and also causing the guide bar 51 to be moved vertically with said presser bar. A spring 52 normally moves the presser bar downwardly and holds the presser foot in yielding engagement with the material. The presser bar 17 may be raised for the insertion of the work through a hand lever 52' or through a foot controlled lever 54. The spring 51^a bears against the block 60 and serves as an auxiliary spring which co-operates with the flat spring 52. The guide bar 51 is offset from the presser bar which receives direct thrust from the spring 52, and this spring 51^a prevents binding action as the guide bar 51 moves up and down.

The feed bar 30 is moved vertically by means of a link 55. Said link is pivoted at 56 to a pin connected to the feed bar 30. Said link 55 at its upper end is pivoted at 57 to the horizontal arm of a rock lever 58, and the rock lever 58 is fulcrumed at 59 to a block 60 fixed to the guide bar 51. This block 60 has a forked end engaging the presser bar 17, and this prevents the block 60 from oscillating in its bearings. The other or vertical arm of the rock lever 58 is connected at 61 to a link 62, and this link in turn is connected at 63 to an arm 64 mounted on the shaft 41. The shaft 41 has a depending arm 65 at the rear end thereof. The arm 65 at its lower end carries a pin 66 provided with a ball which is engaged by an eccentric strap 67, and this eccentric strap co-operates with an eccentric 68 which is adjustably connected to the shaft 7 so that it may be bodily shifted radially relative to said shaft for varying the throw of the eccentric. In Fig. 7 of the drawings, I have shown one way of adjustably connecting the eccentric to the shaft. The eccentric is carried by a plate. The plate and eccentric are formed with a slot 69 which receives the shaft 7. Said plate and eccentric are secured by a pivot bolt 70 to a part fixed to the shaft and this eccentric and plate are adjustable about this pivot. They are held in adjusted positions by a locking bolt 71.

As the main shaft rotates, the eccentric will oscillate the arm 65, and this through the shaft 41 will oscillate the arm 64. The oscillations of the arm 64 will, through the link 62, impart oscillations to the lever 58. The eccentric is so timed that the lever 58 is moved in a counter-clockwise direction about its fulcrum 59 so as to raise the feed bar 30 and the upper feed dog at the same time

that the lower feed dog is moved downwardly away from the material, and this positions the feed dogs for their return movement after which the lever 58 is moved in the opposite direction, and this positively moves the upper feed dog into gripping relation with the material. After the upper feed dog has come into contact with the material the rock lever 58 is given an additional movement. Inasmuch as the feed-bar 75 30 cannot move farther in its downward direction, the pivot 57 of the link 55 becomes a fulcrum and the lever 58 will lift the pivot 59, thus lifting the guide bar 51 and the presser bar 17 connected thereto. This positively raises the presser foot from the material so that it is entirely free of the material while the upper feed dog is partaking of its feeding action. When the lever 58 is moved to raise the upper feed dog the 85 presser foot is first positively lowered onto the material and when it rests thereon then the pivot 59 of the lever becomes a fulcrum point so that a further movement of this lever 58 will raise the feeding foot or feed 90 dog.

From the above it will be noted that the presser foot moves up and down in a vertical plane only, and becomes an abutment for lifting the upper feed dog, while the upper feed dog is positively moved up and down and becomes the abutment for the raising of the presser foot; and the upper feed dog is positively moved backward for its feeding movement during the time while the presser 100 foot is raised and is moved forward for its return movement during the time when the presser foot is in contact with the material. It will be understood that the upper feed dog does not begin to rise until after the 105 presser foot has gripped the material and the presser foot does not begin to rise until after the feed dog has gripped the material.

It is obvious that minor changes in the 110 details of construction and the arrangement of parts may be made without departing from the spirit of the invention, as set forth in the appended claims.

Having thus described the invention, what 115 is claimed as new is:—

1. A sewing machine including in combination a work support, an upper feed dog, a vertically disposed feed bar carrying said upper feed dog, means for pivotally supporting said feed bar at the upper end thereof whereby the same may move up and down, means for engaging the feed bar between its ends for guiding its back and forth and up and down movements, means 120 for moving the feed bar laterally for giving a feeding movement to the feed dog and means for raising the feed bar, said last named means including a rock lever 125 having a substantially horizontal arm, a 13

- link connecting the free end of said arm with said feed bar and means for oscillating said rock lever.
2. A sewing machine including in combination a work support, an upper feed dog, a vertically disposed feed bar carrying said upper feed dog, means for pivotally supporting said feed bar at the upper end thereby of whereby the same may oscillate and move up and down, means for engaging the feed bar between its ends for guiding its back and forth and up and down movements, means for moving the feed bar laterally for giving a feeding movement to the feed dog, means for raising the feed bar, said last named means including a rock lever having a substantially horizontal arm, a link connecting said arm with the feed bar, said link being substantially vertical, said rock lever having a substantially vertical arm, a cross shaft at the rear of the machine, a depending arm carried by the cross shaft and a link connecting said depending arm on the cross shaft with the vertical arm of the rock lever.
3. A sewing machine including in combination a work support, a presser bar, a presser foot carried thereby, an upper feed dog, a vertically disposed feed bar carrying said upper feed dog, means for pivotally supporting said feed bar at its upper end whereby the same may oscillate and move up and down, a rock lever fulcrumed on the presser bar and having a substantially horizontally extending arm, a vertically arranged link connecting the outer end of said arm with the feed bar for raising and lowering the same, means for oscillating the rock lever and means for oscillating the feed bar.
4. A sewing machine including in combination a work support, a presser bar, a presser foot carried thereby, an upper feed dog, a vertically disposed feed bar carrying said upper feed dog, means for pivotally supporting said feed bar at its upper end whereby the same may oscillate and move up and down, a rock lever fulcrumed on the presser bar and having a substantially horizontally extending arm, a vertically arranged link connecting the outer end of said arm with the feed bar for raising and lowering the same, a cross shaft at the rear of the machine, said cross shaft having a downwardly extending arm, said rock lever having a substantially vertical arm and a link connecting said vertical arm with the downwardly extending arm on the cross shaft and means for oscillating the feed bar.
5. A sewing machine including in combination a work support, a presser bar, a presser foot carried thereby, an upper feed dog, a vertically disposed feed bar carrying said upper feed dog, means for pivotally supporting said feed bar at its upper end whereby the same may oscillate and move up and down, a rock lever fulcrumed on the presser bar and having a substantially horizontally extending arm, a vertically arranged link connecting the outer end of said arm with the feed bar for raising and lowering the same, a cross shaft at the rear of the machine, said cross shaft having a downwardly extending arm, said rock lever having a substantially vertical arm and a link connecting said vertical arm with the downwardly extending arm on the cross shaft and means for oscillating the feed bar.
6. A sewing machine including in combination a work support, an upper feed dog, a feed bar carrying said upper feed dog and having an opening formed therein intermediate its ends, a bearing plate having a securing member extending through said opening, said bearing plate being of sufficient size to overlap the feed bar, means for guiding the upper end of the feed bar, means for raising and lowering the feed bar and means for moving the feed bar back and forth.
7. A sewing machine including in combination, an overhanging arm, a work support, an upper feed dog, a vertically disposed feed bar carrying said upper feed dog, said feed bar having an opening formed therein intermediate its ends, a bearing plate for engaging the feed bar adjacent said opening, a screw for securing the bearing plate to the overhanging arm, said feed bar having a vertical slot at its upper end, a fulcrum pin passing through said vertical slot, means for raising and lowering the feed bar and means for moving the feed bar back and forth.
8. A sewing machine including in combination an overhanging arm, a work support, an upper feed dog, a vertically arranged feed bar carrying said upper feed dog, means for supporting the upper end of the feed bar whereby the feed bar may oscillate and move vertically, means intermediate the ends of the feed bar for guiding the same as it moves back and forth and up and down, a cross shaft at the rear side of the overhanging arm, a depending arm carried by the cross shaft, means for oscillating said cross shaft, a lever oscillated by said cross shaft, a vertically disposed link connected to the end of the lever and to said feed bar for moving the same up and down and means for moving the feed bar back and forth.
9. A sewing machine including in combination, an overhanging arm, a work support, an upper feed dog, a vertically arranged feed bar carrying said upper feed dog, means for supporting the upper end of

the feed bar whereby the feed bar may oscillate and move endwise vertically, means intermediate the ends of the feed bar for guiding the same as it moves back and forth and up and down, a cross shaft at the rear side of the overhanging arm, a depending arm carried by the cross shaft, means for oscillating said cross shaft, a lever oscillated by said cross shaft, a vertically disposed link connected to the end of the lever and to said feed bar for moving the same up and down, a rock sleeve mounted on the rock shaft, means for rocking said sleeve, an arm depending from said sleeve, and a substantially horizontally disposed link connecting said arm to the feed bar for moving the same back and forth.

10. The combination of a work support, a

presser foot, a presser bar supporting said presser foot, a guide bar attached to the presser bar and movable up and down therewith, a spring engaging the presser bar and normally forcing the same toward the work support, a spring engaging said guide bar and normally forcing the same downwardly toward the work support, a feeding mechanism including a feed bar located above the work support, a feed dog carried thereby, means for oscillating said feed bar for giving feeding movements to the feed bar, and means for raising and lowering the presser foot and feed dog alternately.

In testimony whereof, we affix our signatures.

JAMES R. MOFFATT.
RALPH S. KELSO.
